United States Patent Office

Des. 191,698
Patented Nov. 7, 1961

191,698

BACON HANGER

Walter H. Krause, Chicago, Ill., assignor to Beacon Metal Products Co., Chicago, Ill., a partnership

Filed June 8, 1960, Ser. No. 60,872

Term of patent 14 years

(Cl. D11—1)

FIG. 1.

FIG. 2.

FIG. 3.

I claim:

The ornamental design for a bacon hanger, as shown.
